UNITED STATES PATENT OFFICE.

HENRY HOWARD, OF CLEVELAND, OHIO, ASSIGNOR TO THE GRASSELLI CHEMICAL COMPANY, OF CLEVELAND, OHIO, A CORPORATION OF OHIO.

DUST-COLLECTING SYSTEM.

Application filed April 28, 1927. Serial No. 187,257.

This invention relates to a device for removing the dust, fume, and smoke from the exterior or metallurgical furnaces, such as zinc smelting furnaces of the Belgian retort type.

These furnaces are usually arranged in blocks, a block being, for example, 110 feet long by 15 to 20 feet wide and from 10 to 12 feet high, the zinc retorts being set into the 10 furnace on the long dimensions in tiers about four high. Such a block will contain about 1400 retorts, 700 on each side.

In the operation of such furnaces during the charging, discharging and cleaning of the retorts, there are produced considerable amounts, of dust, smoke and fumes, which must be removed. Heretofore, it has been the practice to mount a hood or hoods over the furnace and projecting on each side, the 20 hoods being connected by flues to a ventilating stack. The air drawn by the draft of the stack or ventilating fans carries the dust, fumes, and smoke away from the furnace, thus enabling the workmen to do their work 25 without being subjected to objectionable conditions. The emission from the stack of the smoke, etc., has, however, in some cases been found to be a nuisance to the neighborhood, and it was, therefore, proposed to obviate this nuisance by passing the dust-laden 30 gases through a Cottrell dust precipitator. The volume of gases heretofore used was, however, so large that a precipitator of unwieldy size would be required.

Accordingly it is the principal object of this invention to provide an apparatus which will permit the removal of dust and smoke in an efficient and economical manner.

Another object of the invention is to eliminate, from the handling of the dust-carrying gases, all mechanically operated apparatus as well as flues, substituting natural draft for fans and thereby save both initial 40 expense and operating cost.

A further object of the invention is to reduce the volume and thus increase the temperature of the gases so as to give a stronger natural draft, and also to reduce the size of the dust precipitating equipment.

These objects are attained by an especially constructed hood and location of the precipitating device in the natural, direct pass of the dust and fume-laden gases.

My invention consists accordingly of a hood covering the top of the furnace and

extending down its walls, which hood is provided with a throat, or throttle, near the top of the furnace. A convenient form of providing my hood with such a throat is to construct this hood with two shells—an outer, straight-walled shell extending downward over the walls of the furnace, and an inner one fitting snug against the furnace walls, bulging or slanting toward the outer shell, near the top of the furnace—and providing at that throat a cross section much smaller than the area of the hood itself and of its entrance into the dust precipitating equipment. The inner shell covers also, conveniently, the top of the furnace.

Due to this throat, I am able to considerably reduce the amount of air carried through the hood without, in any way, reducing its function of eliminating the fumes and dust discharged from the furnace during distillation, cleaning, or other operations at the retorts.

At the same time I obtain in the hood a gas of higher temperature which increases the natural draft, and, placing the dust precipitating equipment within or directly over the hood, that is to say, in direct connection with it, I am able to eliminate all flues and fans, the precipitating equipment leading directly into the stacks.

In another form of construction of my novel hood, I provide the throat with a throttle which permits variations in its cross section. This feature is shown in Fig. 3 of the accompanying drawings.

In an ordinary hood, a strong wind blowing against one end of the furnace block would result in a very uneven draft. It is quite important, however, in order to insure complete and regular elimination of the dust and fumes around the furnace, to provide for an equal draft in the hood over the entire length of the block.

I accomplish this in a preferred embodiment of my invention by making the hoods on each side of the furnace in several, for instance, five or six, sections, and placing a separate Cottrell, or other dust precipitating device, in approximately the center of each section. This solves that difficulty in a very effective and cheap manner; in fact, the cost of construction is less than if one large Cottrell were used in the center of the block.

The construction of the furnace hood, ac-

cording to my invention, will be readily understood from the accompanying drawings in which

Fig. 1 is a front elevation of the furnace 5 and hood;

Fig. 2 is an end elevation of the same;

Fig. 3 is a vertical section on the line III—III of Fig. 1, but on a much enlarged scale; and

10 Figs. 4 and 5 show details of the hood construction.

Fig. 6 represents an entire furnace block with its dust and fume eliminating device.

Fig. 1 illustrates one full section of the 15 entire block, as many like sections being used as are necessary. 1 is the furnace and 2 is the hood which extends over the entire block. 3, 3 are the retorts and 4, 4 are the usual buck-stays. The hood 2 has an outer shell 20 5 and an inner shell 6, providing a passage for delivering the gases into the base of a dust-precipitator 15, which may be of the usual construction consisting, in this particular instance, of a square pipe 7 within 25 which are mounted the usual discharge and collecting electrodes. The electrical precipitator thus forms part of the vent stack.

As shown in Figs. 3, 4 and 5, the inner shell of the hood is so shaped as to form, 30 with a portion of the outer shell, a contraction or throat 8, which is, by means of an adjustable flexible plate 9, or other suitable means, varied in cross-section to control the flow of the gases therethrough. This adjustable plate is fixed at 10 to the inner shell 35 of the hood, but has at its lower ends slots 11, through which pass screw bolts 12 secured to the inner shell. Wing-nuts 13 enable the adjustable plate to be secured in 40 adjusted position. To facilitate adjustment

of the plates, each is provided with a handle bar 14 hinged thereto. By moving the bar up or down, the adjustable plates will be bulged out or drawn in to vary the cross-section of the throat.

45 The hood is provided with as many adjustable plates as may be necessary to control the throat opening of the hood and provide for the proper flow of gas for the varying conditions.

1 is the furnace block covered by a hood, the outer shell of which is shown as 2 and the inner one as 3; the throat is indicated by the dotted line 4.

50 This hood is divided by the side partitions 5 into six sections.

A Cottrell dust eliminator 15 is located in each section; each of them leads into a separate stack 7, the dust obtained in the Cottrells being collected in a common screw conveyor 8.

55 I claim:

1. A dust and fume collecting device for metallurgical furnaces, comprising a hood having its lower portion extending over the 60 front of the furnace and having a constricted throat portion above the opening of the hood.

65 2. A dust and fume collecting device for metallurgical furnaces, comprising a hood having its lower portion extending over the front of the furnace and having a constricted throat portion above the opening of the hood, said throat portion being provided with means for varying the opening of the 70 throat.

75 In testimony whereof, I affix my signature.

HENRY HOWARD.
